UNITED STATES PATENT OFFICE.

WILLIAM S. KINSLEY, OF READING, MASSACHUSETTS, ASSIGNOR TO THE RUSSELL COMPANY, OF BOSTON, MASSACHUSETTS, A CORPORATION OF MASSACHUSETTS.

TRANSFER MECHANISM.

1,414,699.

Specification of Letters Patent.

Patented May 2, 1922.

Application filed January 5, 1920. Serial No. 349,510.

To all whom it may concern:

Be it known that I, WILLIAM S. KINSLEY, a citizen of the United States, and a resident of Reading, in the county of Middlesex and 5 State of Massachusetts, have invented an Improvement in Transfer Mechanisms, of which the following description, in connection with the accompanying drawings, is a specification, like characters on the drawings 10 representing like parts.

This invention pertains to improvements in transfer mechanisms, and more particularly, though not exclusively, to transfer mechanisms for use in connection with preparing batches of stock for use in woolen 15 or other textile mills.

One use for which the preferred embodiment of my invention herein illustrated and described is particularly adapted is shown 20 diagrammatically in my copending application directed to improvements in apparatus, installations and methods for use in treating textile stock, Serial No. 349,508, filed Jan. 5, 1920.

25 In the drawings, which show a preferred form of one embodiment of my invention:— Figure 1 is a side elevation of a preferred form of truck and parts carried thereby;

Fig. 2 is an end elevation of the apparatus shown in Fig. 1, in connection with a 30 preferred form of apparatus for facilitating discharge of a load of material from the truck; and

Figs. 3 and 4 show details of a portion of 35 the discharge mechanism shown in Fig. 2 and illustrate two different steps in the operation of such mechanism.

Referring to the drawings and to the preferred form of my invention selected for 40 illustrative purposes, I have shown a track including rails 5, on which is mounted a truck including wheels 6 journaled in suitable bearings attached to a truck frame 7 which preferably carries a scale having a base 45 8 and a weighing platform 9, on which is in turn mounted a floor 10, preferably through the medium of channel irons 11. In the preferred form of my invention, I have mounted on the floor and channel irons 10 and 11, the 50 framework including end members 12, 12, which may be and preferably are connected together at one side of the apparatus by a side brace member 13.

Cooperating with the before-described 55 mechanism, I preferably provide a remov-

able, bottomless container or box 14, which may be carried on wheels or rollers 15, 15 adapted to roll on tracks 16, 16 carried by the end frames 12, 12 of the apparatus.

The truck with the scale carried thereby, 60 the box floor carried by the scale, and the bottomless box above the floor may be wheeled along the track 5 to or from any desired point where the box may be filled with stock, preferably through a trap door 65 in the floor above. To prevent the bottomless box from rolling off the truck, I may provide any suitable retaining mechanism, herein shown as spring-pressed detents 17 adapted to project through the rails 16, 16 70 and to chock one or more of the wheels 15. To facilitate emptying of the stock carried by the apparatus hereinbefore described I preferably provide means for moving the bottomless box off the truck and over an 75 opening, herein shown as a hole or trap door 18 in the floor on which the rails 5 are carried, such means preferably providing a support 19 adapted to carry rails 20 in alignment with the rails 16, 16 onto which 80 the wheels 15 may pass so as to bring the bottomless box into the position shown in dotted lines in Fig. 2.

To prevent tipping of the truck-supported apparatus during the transference of the 85 bottomless box from the truck to the dumping support, I may provide the truck with means adapted to steady the same laterally during the transfer operation, herein typified by abutting means preferably including 90 rollers 21 carried by the floor 10, or parts connected thereto carried by the platform of the scale, cooperating with a complementary abutment 22, which may be stationary and carried by the floor. This mechanism 95 prevents tipping of the truck and especially of the parts carried by the scale platform. To hold the truck with the rails 16, 16 in alignment with the rails 20, I preferably provide longitudinal positioning 100 means, herein typified by a rockshaft 23 carrying a rocking lever 24 providing a notch at the upper end thereof adapted to engage with opposite sides of a part carried by the truck, herein shown as a strap 25 secured to 105 one of the end frames 12. The lever 24 may conveniently be rocked into engaging or disengaging position by a foot-controlled lever 26 connected to the lever 24 by any suitable connecting means 27.

When the lever 24 is in the position shown in Fig. 2, the truck is held against movement longitudinally of the rails 5. When the lever 26 is moved in the direction of the arrow 5 shown in Fig. 2, the parts of the lever 24 engaging opposite sides of the strap 25 are drawn out of engagement with the strap 25, so that the truck is free to be pushed along the rails. The weighing operation is preferably performed during the filling of the box while over the floor carried by the truck, while the truck-carried apparatus is not in alignment with the discharge facilitating apparatus so that the functioning of the scale will not be interfered with because of the engagement of the rollers 21 with the abutment 22.

When the parts are in the position shown in Fig. 2, and the truck is held against tipping movement or against movement lengthwise of the rails 5, movement of the bottomless box from the position shown in full lines on the rails 16, 16 to the position shown in dotted lines on the rails 20 may, if desired, be facilitated by any suitable mechanism, but preferably by manually operable means herein typified by a chain 28 passing at one end over a sprocket 29 carried by a relatively short shaft 30, and at the other end by a sprocket 31 which may conveniently be mounted on a shaft 32 of sufficient length to extend to the other end of the support 19 where similar chain and sprocket mechanism cooperating with parts preferably similar to those hereinafter described may be adapted to engage and apply force to move the opposite end of the bottomless box.

I preferably mount on the shaft 32 a hand-wheel 33 to facilitate turning of the same and the sprockets carried thereby.

The chain 28 preferably carries a hook 34 adapted to engage projecting means typified by the pin 35 on the bottomless box and, 45 when the hand-wheel 33 is turned in a clockwise direction as viewed in Fig. 2, the hook 34 will engage the pin 35 and on continued rotation in a clockwise direction the hand-wheel 33 will move the hook, the pin, and consequently the bottomless box, in the direction of the arrow shown in Fig. 3, the position of the box shown in dotted lines in Fig. 2 being ultimately reached, at which time, there being nothing under the bottom of the 55 box, the contents thereof will drop through the opening 18 into the bin or other receiver beneath.

After the discharge operation, the direction of rotation of the hand-wheel 33 will 60 be changed so that it will turn in a contraclockwise direction, at which time the pivoted latch 36 will come into operation to push against the pin 35 and return the now empty bottomless box to its initial position 65 on the truck.

At the conclusion of the return movement, it is desirable to disengage the pivoted latch 36, and I may conveniently perform this by providing the latch, which is pivoted at 37, with a lever arm 38 pivoted to the latch at 70 39 and cooperating with a stop 40 adapted to limit swinging movement of the lever arm 38 relative to the latch in one direction. On the sprocket 29, I provide a pin 41 adapted to engage the lever 38 and, just before the 75 parts assume the position shown in Fig. 4, to rock the latch 36 away from the pin 35.

I prefer to mount the lever 38 in pivoted relation to the latch 36, so that during the bottomless box removing operation, shown 80 in Fig. 3, continued movement of the parts in the direction shown in Fig. 3 will not result in interference of the pin 41 with the lever 38, the latter being permitted to swing out of the way of the pin without moving 85 the latch 36, which during this operation is preferably in contact with a stop 42.

It will be understood that the transfer facilitating mechanism typified by the chain 28, the latch 34 and cooperating parts described above is preferably provided in duplicate, so that both ends of the bottomless box may be engaged during the transfer operation, the pin 35 also being in duplicate 90 as shown in Fig. 1.

The frame 7 of the truck may be provided with extensions 50 to provide handles 51, so that the truck and parts carried thereby may be conveniently pushed or pulled without the pushing or pulling force being 100 directly applied to the parts carried on the scale platform.

Claims.

1. Transfer apparatus including a truck, a floor carried by said truck, a bottomless box 105 adapted to be positioned on said truck above said floor and means including a support independent of said truck for receiving said bottomless box when shifted from said truck, said support sustaining said bottomless box 110 with the bottom thereof open to permit gravity-actuated discharge of the contents thereof.

2. Transfer apparatus comprising, in combination, a support carrying a scale having 115 a platform, guiding means carried by said platform and supporting a bottomless box, supplemental guiding means not carried by said platform for alignment with the first-named guiding means and adapted to permit 120 shifting of said box from said platform to a position where the contents of said box may fall through the opening in the bottom thereof.

3. Transfer apparatus comprising, in combination, a wheeled truck, a box carried by said truck, guiding means operatively interposed between said box and said truck to facilitate shifting of the box from the truck, supplemental guiding means off the truck, 130

said first and second named guiding means being alignable whereby said box may be shifted from one to the other, and means for engaging said box, including a chain-carried hook, to shift the same from one of said guiding means to the other.

4. Transfer apparatus comprising, in combination, a wheeled truck, a box carried by said truck, guiding means operatively interposed between said box and said truck to facilitate shifting of the box from the truck,

supplemental guiding means off the truck, said first and second named guiding means being alignable whereby said box may be shifted from one to the other, and means for engaging said box including a chain-carried hook and latch to shift the same from one of said guiding means to the other and vice versa.

In testimony whereof, I have signed my name to this specification.

WILLIAM S. KINSLEY.
